US00D562848S

(12) **United States Design Patent** (10) **Patent No.:** **US D562,848 S**
Andre et al. (45) **Date of Patent:** **** Feb. 26, 2008**

(54) **HANDHELD PORTABLE COMPUTING DEVICE**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Shin Nishibori**, San Francisco, CA (US); **Matthew Dean Rohrbach**, San Francisco, CA (US); **Douglas B. Satzger**, Menlo Park, CA (US); **Calvin Q. Seid**, Palo Alto, CA (US); **Christopher J. Stringer**, Portola Valley, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/281,264**

(22) Filed: **Jun. 19, 2007**

Related U.S. Application Data

(62) Division of application No. 29/237,232, filed on Aug. 24, 2005, now Pat. No. Des. 553,129.

(57) **CLAIM**

We claim the ornamental design for a handheld portable computing device, substantially as shown and described.

DESCRIPTION

FIG. 1 is a perspective view of a handheld portable computing device in accordance with the present design.

FIG. 2 is a front view for the handheld portable computing device.

FIG. 3 is a rear view for the handheld portable computing device.

FIG. 4 is a bottom view for the handheld portable computing device.

FIG. 5 is a top view for the handheld portable computing device.

FIG. 6 is a right side view for the handheld portable computing device; and,

FIG. 7 is a left side view for the handheld portable computing device.

The broken lines are for illustrative purpose only and form no part of the claimed design.
